MEANS FOR SUPPORTING A PIPE STRING IN A WELL WHILE ADDING TO AND REMOVING PIPE FROM THE STRING

Albert A. Ashton, Dallas, Tex., assignor to The Youngstown Sheet and Tube Company, Youngstown, Ohio, a corporation of Ohio

Filed Nov. 15, 1961, Ser. No. 152,696

1 Claim. (Cl. 248—60)

This invention relates to pipe supports, and more particularly to apparatus for supporting pipe in the well while pipe sections are being added to or removed from the string.

During running or pulling of pipe, such as drill string in wells, it is customary to use slips. At the moment when the pipe is at the desired elevation, slips are positioned about the pipe and the pipe lowered slightly to rest on the slips. With the pipe supported on the slips, a new section of pipe may be added to the string or a section of pipe may be removed from the string.

It is not infrequent that the weight of the string is rather suddenly imposed on the slip assembly and the entire turntable assembly subjected to considerable stress. When the string weight is suddenly imposed on the conventional assembly, this results in the slips biting into the pipe deeper than necessary. Handling of the string in this manner progressively deteriorates the pipe until it is not fit for use in deep wells, or in some cases unfit for use at all.

In drill strings used for very deep wells even slight die marks from slips begin to become objectionable due to the tremendous stresses imposed on the pipe, as failure of the pipe is induced by these die marks.

It is an object of this invention to provide apparatus for suspending of pipe in the well in which the shock of the weight of the string being placed on the supporting apparatus is greatly reduced by permitting the pipe-supporting structure to give as the weight of the pipe is transferred and gradually deaccelerate the downward movement of the pipe.

Another object is to provide apparatus for supporting pipe in the well in which the pipe support means does not employ slips of any type and does not mark the pipe in any way.

Another object is to provide an apparatus which combines the two previously stated objectives to support pipe in the well without marking the pipe and to gradually deaccelerate downward movement of a pipe when the weight of the pipe string is transferred to the apparatus.

Another object is to provide an apparatus for supporting a pipe string in a well without marking the pipe in any manner in which the apparatus is formed in hinged sections and can be readily wrapped around a pipe and supported in the master bushing receptacle in the conventional rotary table.

Another object is to provide apparatus for supporting pipe in which downward movement of a pipe transferred from the traveling block to the device is gradually deaccelerated to reduce the shock load of the weight of a string of pipe being transferred from the traveling block to the rotary table in which the pipe-supporting apparatus is sectioned to permit it to be wrapped around a pipe and supported in the master bushing receptacle of a rotary table.

Other objects, features and advantages of this invention will be apparent from the drawings, the specification and the claim.

In the drawings, wherein like reference numerals indicate like parts, and wherein illustrative embodiments of this invention are shown:

2

FIGURE 1 is an elevational view of a rotary table having a pipe-supporting apparatus constructed in accordance with this invention supported on the rotary table and extending into the master bushing receptacle of the rotary table;

FIGURE 2 is a top plan view of the pipe-supporting apparatus with the top dust covers removed, being partly in section and partly in elevation, and illustrating the construction on the top pedestal of the apparatus;

FIGURE 3 is a view along the lines 3—3 of FIGURE 2; and,

FIGURE 4 is a view partly in elevation and partly in section of a modified form of this invention.

The rotary table indicated generally at 10 may be of any desired form, and in use would be in place on the derrick floor. The pipe support apparatus of this invention is preferably supported on the rotary table by removing the master bushing from the master bushing receptacle 11. It is preferred to support the apparatus in the master bushing receptacle, as this gives stability to the apparatus and prevents rotation of the apparatus while making up and breaking out pipe.

The pipe support apparatus of this invention indicated generally at 12 includes a pedestal base 13 and a pedestal top 14. While the pedestal base and top might each be fabricated from a single piece of material, it is preferred that the pedestal base and top be split vertically into sections and the sections hinged together with the hinge structure shown in FIGURE 1 at 15, 16 and 17. The hinged pedestal and base are latched together by suitable latch means such as bolts and nuts 18, 19 and 20. This facilitates wrapping of the pipe support apparatus about a pipe in the rotary table and lowering of the apparatus into the rotary table while the pipe is in place.

The pedestal base 13 has a depending square-sided skirt 21 which registers with the master bushing receptacle 11 of the rotary table.

The pedestal base has a central bore 22 extending vertically therethrough.

The pedestal top 14 has a central bore 23 extending therethrough in register with the bore 22 of the pedestal base.

Means are provided for preventing relative rotation between the pedestal top and base by providing the lower section of the pedestal top with an outer diameter which will fit within the counterbore 24 which forms a portion of the bore 22 through the pedestal base. A spline 25 in the counterbore 24 cooperates with a slot 26 indicated in dashed lines in the outer periphery of the lower section of the pedestal top. This construction permits movement of the pedestal top vertically relative to the pedestal base while preventing relative rotation therebetween.

A stop is provided for limiting downward movement of the pedestal top relative to the pedestal base by the lower end 27 of the pedestal top engaging the shoulder 28 between the bore 22 and counterbore 24.

A plurality of spline systems 25 and 26 are preferably employed and would provide a dovetail action preventing disassembly of the pedestal base and top when they are swung about hinges 15, 16 and 17 to an open position. To assist the dovetails in this objective and to prevent the possibility of galling in the dovetail system, guide pins, one of which is shown at 29, are carried by the lower extremity of the pedestal top and extend through slot 31 in the pedestal base. The head of guide pin 29 cooperates with the pedestal base on either side of slot 31 to hold the pedestal top sections in place.

Disassembly of the pedestal base and top by upward movement of the pedestal top is prevented both by the guide pins 29 and by a split ring 32 fastened to the upper

end of the pedestal base. Ring 32 overlies the spline section of the pedestal top to limit upward movement thereof.

The pedestal top is provided with means for supporting pipe thereon. In the preferred embodiment the pedestal top has a plurality of ram assemblies for this purpose. As the two halves 30 and 33 of the pedestal top are substantially identical, only one will be explained in detail. Pedestal top 14 is provided in its upper extremity with a ram cavity 34 which opens to the bore 23 in the center of the pedestal top. A ram 35 is slidably mounted in the ram cavity 34 for movement between a retracted position in which bore 23 is clear and an extended position in which ram 35 overlies bore 23 and provides a support for pipe. The confronting sides of the rams are provided with semi-circular openings 36 which are sized to snugly receive the drill pipe with which they are used. As the tool joints are larger in diameter than the pipe, the upper surface 37 of the rams will provide a shoulder on which pipe may rest. Preferably the pipe is provided with tool joints having double upsets 38 and 39 thereon so that the shoulder 41 between the double upsets will provide purchase for the elevators to be attached to the string for raising and lowering the pipe string.

Means are provided for reciprocating the rams 35 between their extended and retracted positions. Preferably this means is provided by a cylinder 42 in the rear face of the ram which cooperates with a piston 43 mounted in the side wall of the pedestal top 14. A suitable seal between the piston and cylinder, such as O-ring 44, permits the fluid under pressure to be introduced into the cylinder 42 through line 45 to move the ram to its extended position. Suitable fluid under pressure may be supplied by pump 46 from reservoir 47. A three-way valve 48 selectively connects the cylinder 42 with the reservoir 47 and with pump 46.

The piston and cylinder also cooperate to prevent cocking of the ram under the weight of the pipe string.

As a part of the means for reciprocating the rams, resilient means are provided, such as springs 49 and 50, in compression between the rams and shoulders 51 and 52 on the top pedestal. When the valve 48 is turned to the position shown in FIGURE 3, the springs 49 and 50 move the rams to retracted position as soon as the weight of the string is removed.

Suitable mud and dust guards 53 are secured over the ram chambers to protect them from contamination.

In order to return the pedestal top to its upper position when pipe is not supported thereon, and to absorb the shock of pipe being transferred from the elevators to the top pedestal, a combination return spring and shock absorber is provided at a plurality of spaced points about the apparatus. Reference is made to FIGURE 3 in which one of the combination return springs and shock absorbers is shown. The shock absorber includes a telescoping housing made up of outer tubular member 54 and inner tubular member 55. The outer tubular member 54 is closed at its lower end by a cap 56 which is secured to the lower pedestal by the bolt 57 and nut 58. The bolt 57 extends through the cap 56 and a seal therebetween is provided by O-ring 59. The bolt 57 has an enlarged section 57a within cylinder 54 to provide a shoulder which bears against the cap 59 to permit the running up of nut 58 to a tight position to hold the shock absorber in place. The upper end of bolt 57 is frusto-conical in shape as shown at 61, and cooperates with a passageway 62 provided in an inwardly extending flange 63 carried at the lower extremity of the telescoping member 55.

Suitable seal means, such as the double seal 64, between the telescoping members 54 and 55 prevents passage of fluid therebetween. The two telescoping members 54 and 55 are filled almost to the top with a suitable hydraulic fluid 65. A slight air space 66 is left in the top of telescoping member 55 below the end closure 67. The end clo-

sure 67 is closed by a plug 68 to permit replenishing of the fluid in the shock absorber. Access to plug 68 is had by removing plug 69 in the floor of ram chamber 34.

The upper pedestal is provided with a circular flange 5 71 which surrounds the upper end of the shock absorber and the shock absorber bears against the pedestal top in the area defined by flange 71.

10 A suitable dust guard is provided by a bellows 72 extending between the circular flange 71 and the outer telescoping member 54.

15 The return spring is provided by a pair of springs 73 and 74 which surround bolt 57 and bear against the lower closure 56 and the in-turned flange 63 of telescoping parts 54 and 55, respectively.

20 In explaining the operation of the device, it will be assumed that it is desired to begin a round-trip with a drill string during drilling of a well. The kelly is withdrawn from the well and the master bushing removed from the rotary table. The pipe support assembly of this 25 invention is then wrapped about the pipe and its sections secured together with latch means 18, 19 and 20 with the apparatus supported in the upper end of the master bushing receptacle of the rotary table 10.

25 Valve 48 is turned to deliver fluid from reservoir 47 through pump 46 to the passageway 75 in piston 43. This fluid fills cylinder 42 and forces the rams 35 out into engagement with the pipe string. The pipe string is then lowered until the tool joint above the apparatus comes into engagement with and rests upon the upper 30 support surface 37 of the rams 35. The drawworks brakes are then released to transfer the load on the traveling block to the apparatus of this invention. While it is desired that the weight of the pipe be gradually transferred, poor judgment may sometimes result in the transfer being made rather rapidly, but no damage will result to the pipe or to the apparatus as the shock will be absorbed by the shock absorbing means.

35 As the weight is transferred to the pedestal top the pedestal top moves down and begins to telescope the telescoping parts 54 and 55 of the shock absorber. As this action occurs, the frusto-conical end 61 of the bolt 57 begins to move further into the hole 62 in the bottom of the upper telescoping member. As it does so, it restricts the flow of fluid through the hole 62 and thus gradually deaccelerates the downwardly moving pedestal top, to thus absorb the shock imposed on the assembly when transferring pipe from the elevators to the pedestal top.

40 After the kelly is broken out and laid down, the elevators engage shoulder 41 of the tool joint and raise the string through the assembly the distance of another length of pipe. As the weight is now removed from the pedestal top, the springs 73 and 74 can return the pedestal top to raised position away from the pedestal bottom 45 in preparation for again supporting the pipe. Of course, before the pipe is raised, the valve 48 will be turned to the position shown in FIGURE 3 to permit springs 49 and 50 to move the rams to retracted position so that they will not interfere with the raising of the pipe.

45 An alternate form of this invention is shown in FIGURE 4. The apparatus of FIGURE 4 is identical with the apparatus of FIGURES 1, 2 and 3 except that the rams 35 have been omitted and the pedestal top is provided with fixed surface 76 for supporting pipe. In 50 this form of the invention an extra set of elevators is employed. These elevators may be of any desired construction. In the use of the apparatus shown in FIGURE 4, the string is raised until a tool joint such as shown at 77 is above the surface 76. The elevators indicated generally at 78 are then wrapped about the pipe and latched together. The string is then lowered until the shoulder 79 on the tool joint engages the complementary shoulder 81 in the upper end of the elevators. As the lower surface 82 of the elevators is resting upon 55 the pipe support surface 76 of the pedestal top 14a, the

weight of the pipe is transferred through the elevators to the top of the pedestal top. The shock absorber system absorbs any shock of this transfer and permits the pedestal top to slowly travel downwardly until the lower end 27 of the pedestal top rests upon the stop at the pedestal base provided by shoulder 28. At this time the string of pipe above tool joint 77 is broken out and laid down. The elevators with which the removed section of pipe was handled are then released and the traveling block attached to the elevators 78 and the pipe in the well again raised and the operation repeated.

From the above it will be seen that the objects of this invention have been attained. A system has been provided which will greatly minimize shock to pipe being transferred from the elevators to the rotary table. The system includes a way of supporting pipe which dispenses with the necessity for slips which damage pipe. Of course, slips could be employed in the conventional manner with the shock absorber system by mounting the slips in the pedestal top, but it is preferred to avoid the use of slips by using the rams 35 or the elevator system of support of FIGURE 4 to completely protect the pipe. It is pointed out that this system will be of great advantage with very deep wells where stress on the pipe and the rotary table are very high.

The foregoing disclosure and description of the invention is illustrative and explanatory thereof and various changes in the size, shape and materials, as well as in the details of the illustrated construction, may be made within the scope of the appended claim without departing from the spirit of the invention.

What is claimed is:

Apparatus for drilling rigs comprising, a pedestal base having a central vertical passageway therethrough, a pedestal top having a central vertical passageway there- 35 through in register with the pedestal base passageway,

5
